UNITED STATES PATENT OFFICE

122,166

DESIGN FOR A SHOE OR SIMILAR ARTICLE

Eugene J. Korda, New York, N. Y.

Application January 20, 1939, Serial No. 82,492

Term of patent 7 years

To all whom it may concern:

Be it known that I, Eugene J. Korda, a citizen of the United States and a resident of the county of Bronx, city and State of New York, with a post office address at No. 41 Union Square West, in the Borough of Manhattan, city and State of New York, have invented a new, original, and ornamental Design for Shoes or Similar Articles, of which the following is a specification, reference being had to the accompanying drawing, forming part thereof, in which

The dominant features of my design reside in the portions shown in full lines.

I claim:

The ornamental design for a shoe or similar article, substantially as shown and described.

EUGENE J. KORDA.
